UNITED STATES PATENT OFFICE.

ALEXANDER CONNIO, OF BUENOS AIRES, ARGENTINA.

CALCULATING-MACHINE.

1,068,982.

Specification of Letters Patent. Patented July 29, 1913.

Application filed March 5, 1913. Serial No. 752,015.

To all whom it may concern:

Be it known that I, ALEXANDER CONNIO, a subject of the King of Italy, residing at Buenos Aires, Argentina, have invented certain new and useful Improvements in Calculating-Machines, of which the following is a specification.

This invention relates to improvements in calculating machines adapted to perform the operations of multiplication, division, etc.

The especial objects of my present invention are to produce a machine of the character stated that can be economically manufactured and easily operated, and that will perform its functions accurately and quickly.

A further object of my invention is to provide a tabulated or scaled ribbon as an element of my calculating machine, which will be immune to thermal and humid atmospheric conditions, thus maintaining a degree of accuracy that is impossible where such influences are not combated.

In the accompanying drawing I have illustrated my invention in a preferred form in the following views:—

Figure 1 is a view partly in side elevation and partly sectional of my complete machine. Fig. 2 is a top-plan view of the operative mechanism of my machine, and Fig. 3 is a plan view of a fragment of the ribbon element of my machine.

Referring to the details of the drawing, 4 represents a metal case which may be of any suitable shape, size or material, to contain and furnish support for the operative mechanism. In the top of the case is an opening surrounded by a grooved frame into which is fitted a glass plate 25 through which the ribbons may be viewed without exposing the latter.

5 represents a standard which is secured by bolts 5^e to the bottom of the case at one side of the latter, and is formed with vertical extensions 5^a, 5^b, 5^h, and with horizontal arms 5^c in which slots 5^g are provided. On the opposite side of the case is mounted a standard 6, which corresponds in shape to its complementary standard 5, but is slideable instead of being fixed. The standard 6 has slotted arms 6^a which correspond to the arms 5^c, and is provided with beveled feet 6^c which slidably engage the rabbeted plates 26 which are screwed to

the bottom of the case. It also has vertical 55 extensions corresponding to the extensions 5^a, 5^b, and 5^h of the standard 5.

7, 7^a represent reels or spools which are mounted on rotatable stub spindles projecting inwardly from the vertical extensions 60 5^a, 5^b, etc., of the standards 5 and 6. The end flanges or rims of these spools are parallel and project a considerable distance from the hubs so as to furnish guides for the ribbons which they are designed to 65 carry.

8 represents boxes which are fixed to the standards 5—6 concentric with the spindles 7^b, and house coil springs 9, one end of which is secured to said spindles and the 70 other to the peripheral wall of the box. The springs in the boxes at one end of the machine are so wound that a constant tension is exerted on all of the spindles regardless of the direction of their rotation, thus 75 subjecting the ribbons which are wound and unwound from said spools to uniform traction of pull.

10, 10^a represent the ribbon elements of my machine. These are made of superposed 80 strips of celluloid and silk tissue secured together by a suitable adhesive so as to withstand the action of the atmospheric heat and humidity. These ribbons have appropriate scales or tables as 10^b indicated on their celluloid faces, the scale on the ribbon 10^a bearing a mathematically fixed relation to the scale on the ribbon 10, as in calculating devices of a similar character. The ends of the ribbons are secured respectively to the hubs 90 of the spools 7, 7^a, and the ribbons run over rollers 11, 11^a, which are mounted on shafts 11^d, 11^e respectively. The inner ends of the rollers 11^a are beveled as at 11^b, and the corresponding ends of the rollers 11 are countersunk or recessed as shown by dotted lines 11^c to receive said beveled ends and thus provide frictional engagement between the opposed rollers. The rollers 11 are formed with boxes to receive the shafts 11^e, as shown by 1 dotted lines Fig. 2. On the outer ends of the shafts 11^d, 11^e are pinions 12, 12^a, which mesh with and are driven by gears 13, 13^a, respectively, which gears are mounted on shafts 14, 14^a suitably journaled in the standards 5, and 6. On the shaft 14 is a crank 15 having a handle 16 on its free end, and on the shaft 14^a is a similar crank 15^a having

handle 16^a. Idlers 17, 17^a are mounted on spindles 18, 19 mounted in the slots 5^c in the standards 5 and 6, and their faces are held in frictional engagement with the ribbons 10, 10^a by blocks 23 adjustable by screws 20 and lock nuts 21, in a well-known manner. The spindles 19 enter boxes 19^a in the idler rollers 17 with a sliding fit.

24 represents a plate arranged below the 10 glass 25 and forming an opaque backing for the ribbons to facilitate the reading of the figures on the latter, through the glass 25. Across the center of the glass 25 is a line or work 25^a which serves as a guide in setting 15 the ribbons for desired calculations.

As a means of shifting the standard 6 with its members, I provide a lever 30 which is pivoted on a stud 31 in the bottom of the casing and has a handle 32 at its free end. 20 The other end of this lever is connected at 29 with a link 28 which is connected at 28^a with a lug 27 extending inwardly from the frame 6. A movement of the free end of the lever in the direction indicated by the arrow 25 will draw the standard inwardly thus bringing into frictional engagement the opposed rollers 11, 11^a and 17, 17^a, whereby rotative movement imparted to the rollers in one standard will be communicated to the opposite rollers in the other standard. To effect 30 the separation of the opposed automatically, I provide springs 27^a secured to the bottom of the casing in the path of the standard 6 and so arranged that the springs will be 35 compressed when the standard is moved inwardly by the lever 30 as described. One of these springs is shown at the left hand of Fig. 1, and it will be understood that the other is correspondingly placed at the right 40 hand.

5^b and 6^b represent lubricating tubes

through which oil may be applied to the shafts 14, 14^a.

From the construction described, it is obvious that by operating the cranks 15, 15^a, 45 the ribbons 10, 10^a will be driven independently of each other through the instrumentality of the gears and rollers described, and that when the opposite rollers are brought 50 into frictional engagement the ribbons will move in unison.

My machine is a mechanical adaptation of the well known principles used in logarithms, and the manner in which its calculating operations are carried out need not 55 therefore be set forth herein. The scales appearing on the ribbons will be coördinated to produce the desired results when the ribbons have been given their proper relative 60 adjustments and then operated in the manner described.

Having thus described my invention, I claim:—

In a calculating machine, a case, the standards supported in said case, a pair of spools 65 and a pair of rollers rotatably mounted on each of said standards, the rollers on one standard and adapted to frictionally engage each other, ribbons having coördinated scales, mounted on said spools and rollers, means for driving the rollers on each standard, and means for shifting one of the standards whereby its rollers will be brought into engagement with the rollers on the complementary standard. 70 75

In testimony whereof I affix my signature in the presence of two witnesses.

ALEXANDER CONNIO.
